[57] CLAIM

The ornamental design for a board for supporting remote controls, as shown and described.

DESCRIPTION

FIG. 1 is a front, top and end perspective view of the board for supporting remote controls showing our new design;

FIG. 2 is a front elevational view thereof;

FIG. 3 is a rear elevational view thereof;

FIG. 4 is an end elevational view thereof, the end opposite being a mirror image of the end shown in FIG. 4;

and,
FIG. 5 is a top plan view thereof, the bottom view being a mirror image of the top view shown in FIG. 5.

FIG. 1

FIG. 2

FIG. 3

FIG. 4

FIG. 5
